SHOE SUPPORTING JACK

Original Filed Sept. 21, 1918 3 Sheets-Sheet 3

UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

SHOE-SUPPORTING JACK.

Original application filed September 21, 1918, Serial No. 255,209. Divided and this application filed March 1, 1920, Serial No. 362,365. Renewed June 15, 1922. Serial No. 568,551.

To all whom it may concern:

Be it known that I, LAURENCE E. TOPHAM, a citizen of the United States, residing at Swampscott, in the county of Essex and State of Massachusetts, have invented certain new and useful Improvements in Shoe-Supporting Jacks; and I do hereby declare the following to be a full, clear, and exact description of the invention, such as will enable others skilled in the art to which it appertains to make and use the same.

This invention relates to shoe supporting jacks and, more particularly, to jacks for use in connection with automatic shoe machines.

It is ordinarily required in automatic machines for operating on shoes that the shoe be located in a predetermined position longitudinally of the jack before being clamped in position.

The adjustment and clamping of the shoe on the jack usually are separate and independent operations and result in the expenditure of considerable labor and time. The proper adjustment of the shoe requires more or less care and when improperly performed an imperfect operation usually results.

The principal objects of the present invention are to improve and simplify the construction and mode of operation of shoe supporting jacks and to produce a novel and improved jack upon which a shoe may be quickly and easily adjusted in a predetermined position and clamped in such position, and which will insure the proper adjustment of the shoe before it is clamped.

With these features in view, the invention consists in certain novel and improved constructions, arrangements and combinations of parts hereinafter described and particularly pointed out in the claims, the advantages of which will be readily understood and appreciated by those skilled in the art.

The features of the invention will be clearly understood from the accompanying drawings illustrating the invention in its preferred form, and the following detailed description of the constructions therein shown.

In the drawings Figure 1 is a view in front elevation, partly in section, of a jack

embodiment of the invention; Fig. 2 is a view in front elevation of the jack with certain of the parts in different positions from those in which they are shown in Fig. 1; Fig. 3 is a plan view of the jack; Fig. 4 is a detail sectional view taken substantially on the line 4—4 of Fig. 1; Fig. 5 is a detail sectional view taken substantially on the line 5—5 of Fig. 1; Fig. 6 is a sectional view taken substantially on the line 6—6 of Fig. 2; and Fig. 7 is a view partly in front elevation and partly in section illustrating certain parts of the jack.

The jack illustrated in the drawing is constructed and arranged so that in jacking a shoe the end of the toe of the shoe is located in a predetermined and unvarying position lengthwise of the jack regardless of the size of the shoe placed on the jack. The shoe is gaged with relation to the jack from the forward point in the bulge of the toe portion of the upper. The jack comprises a spindle 2, a concave toe rest 4 to receive the toe of the lasted shoe and a last pin 6 for insertion in the last pin hole in the last to support the heel end of the shoe. The toe rest is mounted on the upper end of the arm 8 on the jack frame. The last pin 6 is carried by a lever 10 pivoted at 12 on an upwardly projecting arm on a cylindrical slide 14 mounted to slide in a bearing or guide in the central portion of the jack frame. The mounting of the last pin on the slide 14 enables the last pin to be moved toward or from the toe rest by the movement of the slide. The lever 10 is formed with a series of gear teeth which mesh with similar gear teeth formed on a lever 16 pivoted at 17 on the slide 14. As shown clearly in Fig. 1, the slide 14 has a central passageway or bore, and mounted to slide in this bore is a second cylindrical slide 18 also having a central bore. The slide 18 is connected with the lever 16 by means of a rod 20 mounted to slide through an opening in one end of the slide and pivotally connected at one end with the lever, as shown clearly in Figs. 1 and 2. Surrounding the rod 20 within the slide 18 is a comparatively heavy coiled spring 22 interposed between the end wall of the slide and a nut 24 threaded on the other end of the rod. The relative movement of the slide 18 and the rod 20 under

90
95
100
105

the influence of the coiled spring 22 is limited by the engagement of either the end of the rod or the nut 24 with a plug 25 threaded into the end of the slide. The slide 14 is moved longitudinally in its bearing in the jack frame during the jacking of the shoe by the longitudinal movement of the slide 18. The slide 18 is moved longitudinally by the rotation of a sleeve 26 mounted to rotate in suitable bearings in the central portion of the jack frame and carrying a pinion 28 the teeth of which mesh with rack teeth formed on the lower side of the slide. The sleeve 26 is rotated manually to move the slide 18. Before jacking a shoe the slide 14 is adjusted in accordance with the size of the shoe to be sewn, so that when the shoe is placed on the jack the forward end of the toe of the shoe will be located some distance back of the forward end of the toe rest. The lasted shoe when first applied to the jack occupies the position shown in dot and dash lines in Fig. 1, the heel end of the shoe being supported by the last pin and the toe of the shoe resting on the toe support. With the shoe thus located on the jack the sleeve 26 is rotated in a clockwise direction (Figs. 1 and 2), thereby moving the slide 18 to the right. This movement of the slide 18 through the spring 22, the rod 20 and the lever 16 tends to swing the lever 10 in a direction to depress the toe of the shoe. The toe of the shoe, however, rests on the toe support so that it cannot be appreciably depressed. The movement of the slide 18 therefore imparts to the slide 14 a longitudinal movement to the right. This movement of the latter slide carries the shoe forwardly with relation to the jack, the toe of the shoe sliding along the upper surface of the toe rest. The movement of the slide 14 continues until the forward point of the bulge in the toe portion of the upper reaches a definite fixed position longitudinally of the jack when the movement of the said slide is positively arrested.

The devices for thus arresting the movement of the slide comprise a pinion 30 mounted to rotate in a suitable bore in the jack frame and having its teeth in mesh with rack teeth formed on the upper side of the slide 14, a ratchet wheel 32 secured to the pinion 30, and a sliding pawl 34 mounted in a bore in the jack frame and arranged to engage the teeth of the ratchet wheel. The pawl is normally held in engagement with the ratchet wheel by a coiled spring 36. The longitudinal movement of the slide 14 to the right in the jack frame will rotate the pinion 30 and ratchet wheel 32 in a counter-clockwise direction (Figs. 1 and 2). The teeth on the ratchet wheel face in a direction such that the pawl when in engagement therewith will prevent rotation there-

of in a counter-clockwise direction. The pawl is held out of engagement with the ratchet wheel during the movement of the slide 14 to the right by means of a bell crank retaining lever 38 pivoted at 40 on the jack frame, the part of said lever constituting the upper arm thereof having the form of a yoke and embracing the jack frame as shown in Figs. 3 and 6. The lower arm of the retaining lever 38 is arranged to engage the end of a projection 42 formed on the pawl at one side of the apex thereof to hold the pawl out of engagement with the ratchet wheel 32 as shown in Fig. 1. The upper arm of the retaining lever is acted upon by a coiled spring 44 which tends to swing the lever in a direction to elevate the lower arm thereof. The upper arm of the retaining lever is engaged by the lower end of a rod 46 mounted to slide longitudinally in suitable guides in the arm 8 on the jack frame. The upper end of the rod is engaged by the end of the lower arm of a bell crank feeler lever 48 pivoted at 50 in a central slot in the toe rest. The upper arm of the feeler lever 48 is located in position to be engaged by the bulge in the toe portion of the upper of a shoe applied to the jack.

When the shoe is initially placed on the jack the parts are located substantially in the positions shown in Fig. 1, the pawl 34 being held out of engagement with the ratchet wheel 32 by the engagement of the end of the lower arm of the retaining lever 38 with the end of the projection 42 on the pawl, and the upper arm of the feeler lever 48 being located in position to be engaged by the toe portion of the upper of the shoe as the toe of the shoe is moved forwardly along the toe rest in jacking the shoe. As along the upper surface of the toe rest the slide 14 is moved forwardly in the jack frame by the rotation of the sleeve 26 and the forward point of the bulge in the toe portion of the upper reaches a definite fixed position longitudinally of the jack when the movement of the said slide is positively arrested.

The devices for thus arresting the movement of the slide comprise a pinion 30 mounted to rotate in a suitable bore in the jack frame and having its teeth in mesh with rack teeth formed on the upper side of the slide 14, a ratchet wheel 32 secured to the pinion 30, and a sliding pawl 34 mounted in a bore in the jack frame and arranged to engage the teeth of the ratchet wheel. The pawl is normally held in engagement with the ratchet wheel by a coiled spring 36. The longitudinal movement of the slide 14 to the right in the jack frame will rotate the pinion 30 and ratchet wheel 32 in a counter-clockwise direction (Figs. 1 and 2). The teeth on the ratchet wheel face in a direction such that the pawl when in engagement therewith will prevent rotation there-

of in a counter-clockwise direction. The pawl is held out of engagement with the ratchet wheel during the movement of the slide 14 to the right by means of a bell crank retaining lever 38 pivoted at 40 on the jack frame, the part of said lever constituting the upper arm thereof having the form of a yoke and embracing the jack frame as shown in Figs. 3 and 6. The lower arm of the retaining lever 38 is arranged to engage the end of a projection 42 formed on the pawl at one side of the apex thereof to hold the pawl out of engagement with the ratchet wheel 32 as shown in Fig. 1. The upper arm of the retaining lever is acted upon by a coiled spring 44 which tends to swing the lever in a direction to elevate the lower arm thereof. The upper arm of the retaining lever is engaged by the lower end of a rod 46 mounted to slide longitudinally in suitable guides in the arm 8 on the jack frame. The upper end of the rod is engaged by the end of the lower arm of a bell crank feeler lever 48 pivoted at 50 in a central slot in the toe rest. The upper arm of the feeler lever 48 is located in position to be engaged by the bulge in the toe portion of the upper of a shoe applied to the jack.

When the shoe is initially placed on the jack the parts are located substantially in the positions shown in Fig. 1, the pawl 34 being held out of engagement with the ratchet wheel 32 by the engagement of the end of the lower arm of the retaining lever 38 with the end of the projection 42 on the pawl, and the upper arm of the feeler lever 48 being located in position to be engaged by the toe portion of the upper of the shoe as the toe of the shoe is moved forwardly along the toe rest in jacking the shoe. As along the upper surface of the toe rest the slide 14 is moved forwardly in the jack frame by the rotation of the sleeve 26 and the forward point of the bulge in the toe portion of the upper reaches a definite fixed position longitudinally of the jack when the movement of the said slide is positively arrested.

The devices for thus arresting the movement of the slide comprise a pinion 30 mounted to rotate in a suitable bore in the jack frame and having its teeth in mesh with rack teeth formed on the upper side of the slide 14, a ratchet wheel 32 secured to the pinion 30, and a sliding pawl 34 mounted in a bore in the jack frame and arranged to engage the teeth of the ratchet wheel. The pawl is normally held in engagement with the ratchet wheel by a coiled spring 36. The longitudinal movement of the slide 14 to the right in the jack frame will rotate the pinion 30 and ratchet wheel 32 in a counter-clockwise direction (Figs. 1 and 2). The teeth on the ratchet wheel face in a direction such that the pawl when in engagement therewith will prevent rotation there-

of in a counter-clockwise direction. The pawl is held out of engagement with the ratchet wheel during the movement of the slide 14 to the right by means of a bell crank retaining lever 38 pivoted at 40 on the jack frame, the part of said lever constituting the upper arm thereof having the form of a yoke and embracing the jack frame as shown in Figs. 3 and 6. The lower arm of the retaining lever 38 is arranged to engage the end of a projection 42 formed on the pawl at one side of the apex thereof to hold the pawl out of engagement with the ratchet wheel 32 as shown in Fig. 1. The upper arm of the retaining lever is acted upon by a coiled spring 44 which tends to swing the lever in a direction to elevate the lower arm thereof. The upper arm of the retaining lever is engaged by the lower end of a rod 46 mounted to slide longitudinally in suitable guides in the arm 8 on the jack frame. The upper end of the rod is engaged by the end of the lower arm of a bell crank feeler lever 48 pivoted at 50 in a central slot in the toe rest. The upper arm of the feeler lever 48 is located in position to be engaged by the bulge in the toe portion of the upper of a shoe applied to the jack.

When the shoe is initially placed on the jack the parts are located substantially in the positions shown in Fig. 1, the pawl 34 being held out of engagement with the ratchet wheel 32 by the engagement of the end of the lower arm of the retaining lever 38 with the end of the projection 42 on the pawl, and the upper arm of the feeler lever 48 being located in position to be engaged by the toe portion of the upper of the shoe as the toe of the shoe is moved forwardly along the toe rest in jacking the shoe. As along the upper surface of the toe rest the slide 14 is moved forwardly in the jack frame by the rotation of the sleeve 26 and the forward point of the bulge in the toe portion of the upper reaches a definite fixed position longitudinally of the jack when the movement of the said slide is positively arrested.

The devices for thus arresting the movement of the slide comprise a pinion 30 mounted to rotate in a suitable bore in the jack frame and having its teeth in mesh with rack teeth formed on the upper side of the slide 14, a ratchet wheel 32 secured to the pinion 30, and a sliding pawl 34 mounted in a bore in the jack frame and arranged to engage the teeth of the ratchet wheel. The pawl is normally held in engagement with the ratchet wheel by a coiled spring 36. The longitudinal movement of the slide 14 to the right in the jack frame will rotate the pinion 30 and ratchet wheel 32 in a counter-clockwise direction (Figs. 1 and 2). The teeth on the ratchet wheel face in a direction such that the pawl when in engagement therewith will prevent rotation there-

18 independently of the slide 14, and through the spring 22 the rod 20 and the lever 16 the lever 10 is tilted slightly to press the toe of the shoe firmly down against 5 the toe rest. The movement of the sleeve 26 is continued until the spring 22 is somewhat compressed so that the spring will press the toe of the shoe against the toe rest with considerable pressure to clamp the 10 shoe to the jack. In order to prevent reverse or counter-clockwise rotation of the gear 28, a pawl 52 is mounted to slide laterally in the jack frame and is arranged to engage ratchet teeth 54 formed on the 15 inner face of a flange on the sleeve 26. The pawl 52 is held in engagement with the ratchet teeth 54 by a coiled spring 56 acting on a longitudinally movable rod 57 secured at one end to the pawl (see Fig. 5). 20 The pawl 52 acting on the ratchet teeth 54 will thus lock the gear 28 and the slide 18 in position.

To enable the sleeve 26 to be turned by the operator, an operating sleeve 58 is mounted 25 loosely on the outer end of the sleeve 26, the sleeve 58 having radially extending arms formed upon its outer end to enable it to be turned readily by hand. The sleeve 58 is connected with the sleeve 26 by means of a 30 screw 60 mounted in the sleeve 58 and having its inner end engaged in a slot 62 in the sleeve 26. The slot 62 has the shape shown clearly in Fig. 3. The shape of the slot enables the sleeve 58 to be moved longitudinally of the sleeve 26. To enable the pawl 52 to be thrown out of engagement with the ratchet teeth 54, a rod 64 is mounted to slide 35 in the central bore in the sleeve 26 and is arranged to engage at its inner end a projection on the pawl. A coiled spring 66 is mounted on the reduced outer end of the rod 64 and is interposed between a shoulder on the rod and a bushing 68 threaded into the sleeve 58, and having a central opening 40 through which the rod passes. The inward movement of the rod 64 relative to the sleeve 58 is limited by the engagement of a collar 70 mounted on the outer end of the rod with the bushing. When the sleeve 58 is in its 45 outer position on the sleeve 26, as shown in Fig. 6, the bushing 68 is engaged with the collar 70 and the rod 64 is held in its outer position in the sleeve 26, allowing the pawl 52 to be held in engagement with the ratchet teeth 54 by the action of the spring 56. In 50 jacking the shoe the sleeve 58 is located in its outer position on the sleeve 26, as shown in Fig. 6, and is turned in a clockwise direction. Through the connection between the sleeve 58 and the sleeve 26 the latter sleeve is turned in a clockwise direction to actuate the slide 18 to locate the shoe in a predetermined position on the jack and to secure the same in such position as above described. 55 In unjacking the shoe the sleeve 58 is pushed

inwardly relatively to the sleeve 26 to engage the screw 60 in the inner part of the slot 62, and is then turned in a clockwise direction. While the sleeve 58 is moved inwardly relatively to the sleeve 26 the pawl 52 is held from moving out of engagement with the ratchet teeth 54 by the lateral pressure of the ratchet teeth on the pawl due to the action of the coiled spring 56, and the movement of the sleeve 58 compresses the 60 coiled spring 66. As the sleeve 58 is turned in a clockwise direction the screw 60 engages the right hand end of the inner part of the slot 62 which is formed to allow considerable lost motion between the sleeve 58 and the sleeve 26 and the sleeve 26 is turned against the tension exerted by the spring 22 thereby relieving the pressure of the ratchet teeth 54 on the pawl 52. The coiled spring 66 which is considerably heavier than the coiled spring 56 then moves the rod 64 inwardly in the sleeve 26 thereby moving the pawl 52 against the action of the spring 56 to disengage the pawl from the ratchet teeth 54. The sleeve 58 is then turned in a 70 counter-clockwise direction. By this counter-clockwise turning movement of the sleeve 58 the sleeve 26 is turned in a counter-clockwise direction to actuate the slide 18 first to relieve the pressure of the toe on the toe rest, and then to move the slide 14 and the shoe therewith rearwardly of the jack frame so that the shoe may be readily removed from the jack. To reset the pawl 34 and the retaining lever 38 in the positions 75 shown in Fig. 1 the pawl is disengaged from the ratchet wheel by the turning movement of the sleeve 58 in a counter-clockwise direction in unjacking the shoe. To this end a lever 72 is mounted to rotate on the sleeve 26 and is formed with a fork at its upper end which embraces the head of a screw 74 mounted on the pawl 34. The lever 72 is also formed with a cone-shaped recess 76 adapted to receive the cone-shaped inner 80 end of the sleeve 58. When the sleeve 58 is in its outer position on the sleeve 26, the inner end of the sleeve 58 is disengaged from the recess 76, as shown in Fig. 6. When the sleeve 58 is moved inwardly relatively to the sleeve 26 and is turned in a clockwise direction, the inner end of the sleeve 58 is engaged in the recess 76 but is held out of contact with the lever 72 by the engagement of the screw 60 with the inner edge of the inner part of the slot 62 which is inclined as shown clearly in Fig. 3. During the movement of the sleeve 58 in a counter-clockwise direction in unjacking the shoe said sleeve moves independently of the sleeve 26 carrying the screw 60 into the left hand end of the inner part of the slot 62. The inner end of the sleeve 58 is then engaged with the lever 72 in the recess 76 and through the frictional engagement between the sleeve 85

and the lever the lever is actuated to retract the pawl 34. Upon the retraction of the pawl the retaining lever 38 is actuated by the spring 44 to elevate the lower arm there- 5 of into position to engage the end of the projection 42 on the pawl.

With a jack of the construction above described, a lasted shoe may be quickly and easily secured in position on the jack 10 with the forward point in the bulge at the toe portion of the upper in a predetermined and unvarying position with relation to the jack regardless of the size of the shoe placed on the jack. It is also to 15 be noted that with this jack construction the operator cannot jack the shoe without locating the shoe properly with relation to the jack, the operation of the mechanism for securing the shoe on the jack being controlled by the position of the shoe.

Having explained the nature and object of the invention, and having specifically described a jack embodying the various features of the invention in their preferred 25 forms, what is claimed is:

1. A jack for shoe machines having, in combination, a heel support, a toe rest, an actuating member arranged to operate during a continuous movement thereof in one direction to adjust the shoe longitudinally of the jack and to clamp the shoe on the jack, mechanism for stopping the shoe adjusting action and for causing the initiation of the shoe clamping action of said 30 member, and means for tripping said mechanism when the shoe is located in a predetermined position on the jack.

2. A jack for shoe machines having, in combination, a heel support and a toe rest 40 relatively movable to locate the shoe with relation to the jack and to clamp the shoe on the jack, a single operating member arranged to produce both the relative shoe locating movements and the relative shoe 45 clamping movements of the heel support and toe rest during a continuous movement of said member in one direction, mechanism for stopping the relative shoe locating movement of the heel support and toe rest and 50 causing the initiation of the relative shoe clamping movement of the same, and means for tripping said mechanism when the shoe is located in a predetermined position on the jack.

3. A jack for shoe machines having, in combination, a tilting heel support and a toe rest relatively movable toward and from each other, an actuating member operating during a continuous movement thereof in 60 one direction, first to move the heel support and toe rest relatively toward each other to locate the shoe in a predetermined position on the jack, and then to tilt the heel support to force the toe of the shoe against the toe rest and thereby clamp the shoe

on the jack, mechanism for stopping the relative movement of the heel support and toe rest toward each other and for causing the initiation of the tilting movement of the heel support and means for tripping said mechanism when the shoe is located in a predetermined position on the jack.

4. A jack for shoe machines having, in combination, a heel support and a toe rest relatively movable toward and from each other, a member connected for actuation with one of said parts during their relative movement toward each other, and a shoe locating stop arranged to engage directly said member to stop the relative movement of the heel support and toe rest toward each other when the shoe is located in a predetermined position on the jack.

5. A jack for shoe machines having, in combination, a heel support, a toe rest, a slide connected with one of said parts, a rotatable shaft, gearing connecting the shaft and the slide, a ratchet wheel mounted on the shaft, a pawl for engaging the ratchet wheel normally held out of engagement therewith, and means for throwing in the pawl to stop the rotation of the ratchet wheel and the movement of the slide during the relative movement of the heel support and toe rest toward each other when the shoe is brought to a predetermined position relative to the jack.

6. A jack for shoe machines having, in combination, a heel support and a toe rest relatively movable toward and from each other, a slide upon which one of said parts is mounted, a rotatable shaft, gearing connecting the shaft and slide, a ratchet wheel mounted on a shaft, a pawl for engagement with the ratchet wheel, a feeler arranged to be engaged by the toe of the shoe, and connections between the feeler and the pawl for holding the pawl out of engagement with the ratchet wheel when the toe of the shoe is located out of contact with the feeler and for causing the pawl to be thrown into engagement with the ratchet wheel to stop the rotation thereof and the movement of the slide when the shoe is located in a predetermined position on the jack.

7. A jack for shoe machines having, in combination, a heel support and a toe rest relatively movable toward and from each other, a member connected for actuation with one of said parts during their relative movement, a stop for engagement with said member to arrest the relative movement of the heel support and toe rest toward each other normally located out of position to engage said member, a feeler for engagement with the shoe, and connections between the feeler and the stop arranged to hold the stop out of operating position while the shoe is out of contact with the feeler and to cause the stop to be thrown into operative

position when the feeler is engaged and actuated by the shoe.

8. A jack for shoe machines having, in combination, a heel support and a toe rest relatively movable toward and from each other, a stop for arresting the relative movement of the heel support and the toe rest toward each other, a feeler for engagement with the shoe, and connections intermediate the feeler and the stop for controlling the action of the stop.

9. A jack for shoe machines having, in combination, a jack frame, a toe rest mounted on the jack frame, a slide, a heel support pivoted on the slide, a second slide, connections including a spring intermediate the second slide and the heel support for tilting the heel support, and means for moving the first slide to adjust the shoe longitudinally of the last and for moving the second slide to tilt the heel support in a direction to force the toe of the shoe against the toe rest and thereby clamp the shoe on the jack.

10. A jack for shoe machines having, in combination, a jack frame, a toe rest mounted on the jack frame, a slide, a heel support pivoted on the slide, a second slide mounted for movement in a direction substantially parallel with the first slide, connections including a spring intermediate the second slide and the heel support for tilting the heel support, and means acting on the second slide and operating during a continuous movement thereof in one direction first to move the slides together to adjust the heel support toward the toe rest to locate the shoe in a predetermined position longitudinally of the last and then to move the second slide independently of the first slide to tilt the heel support and thereby force the toe of the shoe against the toe rest to clamp the shoe on the last.

11. A jack for shoe machines having, in combination, a jack frame, a toe rest carried by the jack frame, a slide, a heel support pivoted on the slide, a second slide mounted for movement substantially parallel with the first slide, connections including a spring intermediate the second slide and the heel support for tilting the heel support, a rotatable shaft, gearing connecting the second slide and the shaft operating during a continuous movement of the shaft in one direction, first to move the slides together to adjust the heel support toward the toe rest to locate the shoe in a predetermined position lengthwise of the last and then to move the second slide independently of the first slide to tilt the heel support and thereby force the toe of the shoe against the toe rest to clamp the shoe on the jack, means for locking the shaft in position, and an operating handle for turning the shaft and for disengaging the locking means.

12. A jack for shoe machines having, in

combination, parts movable to a position to receive the shoe, and mechanism comprising connected cooperating elements coacting when actuated to move the parts to adjust the shoe from receiving to a predetermined position on the jack and clamp the shoe in adjusted position.

13. A jack for shoe machines having, in combination, a pivotally mounted heel support and a toe rest relatively movable towards and from each other, and mechanism comprising connected cooperating elements coacting when actuated to move the heel support and toe rest relatively toward each other to locate the shoe in a predetermined position on the jack and to tilt the heel support to force the toe of the shoe against the toe rest and clamp the shoe on the jack.

14. A jack for shoe machines having, in combination, a heel support and a toe rest relatively movable toward and from each other to adjust the shoe on the jack, and means for stopping the relative movement of the heel support and toe rest when the shoe reaches a predetermined position.

15. A jack for shoe machines having, in combination, a heel support and a toe rest relatively movable toward and from each other to adjust the shoe on the jack, and means controlled by the shoe for stopping the relative movement of the heel support and toe rest.

16. A jack for shoe machines having, in combination, a heel support and a toe rest relatively movable toward and from each other to adjust the shoe on the jack, a feeler for engagement with the shoe, and means controlled by the feeler for stopping the relative movement of the heel support and toe rest.

17. A jack for shoe machines having, in combination, a heel support, a toe rest, mechanism for relatively actuating the heel support and toe rest to adjust the shoe on the jack, and a stop device acting on the actuating mechanism to stop the relative movement of the heel support and toe rest when the shoe reaches a predetermined position.

18. A jack for shoe machines having, in combination, a heel support, a toe rest, and mechanism comprising connected cooperating elements coacting when actuated to adjust the shoe longitudinally of the jack and thereafter clamp the shoe on the jack.

19. A jack for shoe machines having, in combination, a heel support comprising a last pin, a toe rest, and mechanism comprising connected cooperating elements coacting when actuated to move the heel support and toe rest relatively to locate the shoe longitudinally on the jack and to clamp the shoe between the last pin and toe rest.
